UNITED STATES PATENT OFFICE.

BIRNEY C. BATCHELLER, OF BROOKLYN, NEW YORK, ASSIGNOR TO BEMIS BRO.
BAG CO., OF ST. LOUIS, MISSOURI, A CORPORATION OF MISSOURI.

BAG-TURNING MACHINE.

Application filed January 16, 1922. Serial No. 529,561.

To all whom it may concern:

Be it known that I, BIRNEY C. BATCHELLER, a citizen of the United States of America, a resident of Brooklyn, in the county of 5 Kings, State of New York, have invented certain new and useful Improvements in Bag-Turning Machines, of which the following is a full, clear, and exact description, reference being had to the accompanying 10 drawings, forming a part of this specification.

This invention relates to improvements in bag-turning machines, one of the objects being to provide an efficient means for holding 15 the bags during the turning operations. As an illustration of this feature of the invention, I will hereafter describe a pair of bag-holding arms adapted to enter the mouth of a bag and yielding means whereby 20 one of said arms is forced away from the other to frictionally secure the bag, the latter being stripped from said arms during the bag-turning operation. To receive the bag, one of the bag-holding arms moves to- 25 ward the other and both arms preferably move away from the path of a bag-turning member. The mouth of the bag is slipped over these arms and a spring forces one arm away from the other to open the 30 mouth of the bag and frictionally engage the arms with the bag. The bag itself limits the motion of the spring-actuated arm, and this compensates for variations in the dimensions of the bags and insures the desired frictional engagement between the 35 bag-holding arms and the bag.

Another object is to produce a simple and effective bag-turning device adapted to enter and turn the bag held by a bag-holder. 40 This feature is illustrated by a pair of bag-turning members in the form of curved rods movable about different axes, so as to enter the mouth of the bag and move in lines diverging from the mouth to the corners at the 45 closed end of the bag. The axes of these curved rods lie at an angle to each other, and the parts are so arranged that the bag-engaging ends of the rods enter the mouth of the bag and move in diverging lines until 50 they engage opposite sides of the bag. Thereupon, the ends of the rods slide along the bag and effectively turn the corners at

the closed end thereof. The bag-turning rods are preferably yieldable, so their ends will frictionally engage opposite sides of the bag while the operating means is tending to move said ends in diverging paths.

A further object is to produce a bag-turning machine that can be easily and quickly adjusted to receive bags of different widths. 60 The various bag-holding and turning elements are arranged in pairs at opposite sides of the machine, and the elements at one side are mounted on a support which can be adjusted toward and away from the other side of the machine. More specifically stated, the machine includes a pair of supports each provided with a bag-turning member, a bag-holding member and other mechanism for operating on only one side of the bag, 65 and the supports are adjustable toward and away from each other to vary the distances between the companion members at opposite sides of the machine. By merely moving these supports, the entire machine can be 70 properly adjusted for bags of different widths.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends 80 changes, variations and modifications which come within the scope of the claims hereunto appended.

Fig. I is a side elevation of a bag-turning machine embodying the features of this 90 invention.

Fig. II is an enlarged vertical section illustrating a rack and pinion through which motion is transmitted to an oscillatory bag-holder.

Fig. III is a front elevation of the machine, parts being broken away to show an adjusting screw.

Fig. IV is a top view of the bag-turning rods and their bearings.

Fig. V is a section taken approximately on the line V—V, in Fig. I, showing the bag-holding grippers and the means for opening the same.

2
Fig. VI is a front elevation, partly in section, of the elements at the lower portion of Fig. V.

5 Fig. VII is an enlarged vertical section taken approximately on the line VII—VII in Fig. III, and showing mechanism at the front of the machine.

10 1 designates a table (Fig. I) upon which a pile of bags A is supported. An operator removes the bags, one at a time, from the table and places them on a bag-holder having arms 2 and 3 adapted to lie in the mouth of the bag to be turned. Bag-turning members 4, preferably in the form of long, 15 curved rods, or sticks, are movable in arcuate paths, as suggested by dotted lines in Fig. I, to turn the bags, stripping them from the bag-holder and forcing their closed ends between the gripping jaws 6 and 7, as 20 will be hereafter described. The bag-holder comprises a pair of oscillatory supporting members 8 (Figs. I, III and VII) mounted on pivots 9 and movable from the position shown by full lines in Fig. I to the position 25 shown by dotted lines. Each oscillatory supporting member 8 is provided with a non-rotary rod 10 to which a bag-holding arm 3 is secured, and an oscillatory shaft 11 to which a bag-holding arm 2 is secured. 30 The arm 3 is not movable about the axis of rod 10, but the shaft 11 can be turned to move the arm 2 toward said arm 3, as indicated by dotted lines in Fig. I.

35 Each oscillatory supporting member 8 is provided with operating means including an oscillatory shaft 12 (Figs. I, II and III) to which a crank arm 13 is secured, and a connecting rod 14 connecting said crank arm to the member 8. Each shaft 12 is 40 provided with a pinion 15 (Fig. II) meshing with a rack bar 16 (Figs. I, II and III), said rack bar being pivoted to a rotary crank 17 on a shaft 18. The rack bar and pinion are enclosed by a housing 19 pivotally mounted on shaft 12 and having a tubular portion whereby the rack bar 16 is guided and retained in mesh with the pinion 15. Through the medium of the mechanism just described, each oscillatory supporting 45 member 8 is shifted from the bag-receiving position shown by dotted lines in Fig. I to the bag-turning position shown by full lines. When the oscillatory supporting members 8 move to the position indicated by dotted 50 lines, the arms 2 move toward their companion arms 3, as will be hereafter described, so the bags can be readily slipped onto the arms 2 and 3 while the companion arms are located adjacent to each other at 55 points entirely beyond the paths of the bag-turning members 4.

60 The means for moving the bag-holding arms 2 toward and away from the arms 3 includes two sets of mechanisms, one set for each pair of arms 2 and 3, as shown by Figs.

I, III and VII. Each of these sets comprises an operating arm 20 rigidly secured to shaft 11, a connecting rod 21 having its upper end pivoted to arm 20 and its lower end pivoted at 22 to a lever 23, the latter being fulcrumed at 24 and connected to the lower end of a rod 25 having its upper end pivoted to an arm 26 which is pivoted at 27 (Fig. VII) and provided with a roller 28 adapted to be engaged by a rotary cam 29 fixed to the shaft 18. When the parts occupy the positions shown by Fig. VII, the roller 28 is separated from the cam 29. At this time a tension spring 30 acts upon the mechanism just described to yieldingly force arm 2 away from its companion bag-holding arm 3. In Fig. VII, note that the tension spring 30 tends to impart an upward motion to the left end of lever 23, thereby placing the connecting rod 21 under tension, so as to transmit power through the operating arm 20 to the bag-holding arm 2, thereby yieldingly forcing arm 2 away from arm 3. These arms lie in the bag A, and the motion of arm 2 is limited by the bag itself, and not by the cam 29 and roller 28. This compensates for variations in dimensions of the bags and insures the desired frictional engagement between the bag-holding arms 2 and 3 and the inner face of the bag. While a bag is frictionally held in this manner, the bag-turning rods 4 move downwardly to turn the bag, as will be hereafter described, the bag being eventually stripped from the arms 2 and 3.

65 When the supporting members 8 move from the position shown by full lines in Figs. I and VII to the position shown by dotted lines in Fig. I, each cam 29 (Figs. III and VII) engages a roller 28 on an arm 26, with the result of depressing vertical rod 25 and transmitting motion through lever 23, rod 21 and arm 20 to bag-holding arm 2, thereby moving said arm 2 toward the arm 3. As the cam 29 continues in motion, the arm 2 is held adjacent to the arm 3 so as to give the operator an opportunity to slip a bag over the adjacent arms, and the cam is eventually separated from roller 28, as suggested in Fig. VII, to permit spring 30 to act upon arm 2, as previously pointed out. The cam 29 forces arm 2 toward arm 3, and the spring 30 is utilized to yieldingly move arm 2 away from arm 3.

70 The mechanism just described is supported partly by the stationary frame of the machine and partly by the oscillatory supporting members 8 which carry the arms 2 and 3. Each oscillatory member 8 is constantly in motion, and such motion should not materially affect the means for oscillating arm 2 about the axis of its shaft 11. Each arm 2 is therefore acted upon by a set of mechanism having a pivotal connection 75 22 (Fig. VII) located near and in approxi- 80 85 90 95 100 105 110 115 120 125 130

mate alinement with the pivot 9 (Fig. I) which supports the member 8. As a consequence, when a member 8 swings about the axis of its pivotal support, the rod 21 (Fig. 5 VII) moves about the axis of its pivotal connection 22, so the oscillatory motion of the member 8 does not materially displace the mechanism for transmitting motion to arm 2.

10 The curved bag-turning rods 4 have their upper ends secured in sockets 31 at the upper ends of rigid operating arms 32. Each socket 31 (Fig. VII) is pivoted at 33 to the upper end of an arm 32, and the socket can 15 be adjusted about the axis of the pivot to properly locate its rod 4. After a socket has been adjusted, it is secured by means of screws 34 passing through slots 35 in arm 32 (Fig. VII) and screwed into the socket, said 20 screws having heads adapted to frictionally engage the arm 32 so as to secure the socket.

Each arm 32 is rigidly secured to a short shaft 36 mounted in a bearing 37, as shown by Figs. I, III and IV. The axes of shafts 36 lie at an angle to each other, (Fig. IV), and each bag-turning rod 4 is preferably concentric with the axis of its shaft 36. However, since the shafts 36 lie at an angle to each other, it will be apparent that the 30 rods 4 do not travel in parallel paths. These curved rods are preferably made of elastic metal, and their bag-engaging lower ends advance in true arcuate lines diverging from the mouth of the bag to the sides of the bag.

35 When the bag-turning rods occupy their elevated positions (Figs. I and III), their lower ends lie adjacent to each other. As the rods move downwardly about the axes of shafts 36, they pass through the mouth of the bag A held by arms 2 and 3, and at the same time the bag-engaging ends of these arms move away from each other, so as to engage the sides of the bag. The bag-engaging ends are thus freely inserted into the bag and moved away from each other to frictionally engage the opposite sides of the bags. The elastic rods will then yield, for they cannot move away from each other after they have been forced into firm engagement with the sides of the bag, and the ends of said rods will finally engage the corners at the closed ends of the bag, so as to positively turn the corners. Thereupon, the bag is gradually stripped from the bag-holding arms 2 and 3, and its closed end is forced into a gripping device, as will be presently described.

The means for oscillating the bag-turning rods 4 comprises a pair of cranks 38 (Figs. I, III and VII), and connecting rods 39 extending from said cranks to the arms 32. The shafts 18 are parallel with each other, and the crank arms 38 move about the axis of these shafts, while the long arms 32 move 40 about the axes of shafts 36 which lie at an

angle to each other. Therefore, the ends of the connecting rods 39 are flexibly secured by means of ball and socket joints 40, shown in Figs. III and VII.

After a bag has been turned, the bag-engaging ends of the rods 4 force the closed end of the bag into a gripping device including jaws 6 and 7, and the bags are permitted to accumulate in the gripping device. As shown by Fig. I, several of these gripping devices are arranged about the axis of a shaft 41. The means for supporting the gripping devices includes a pair of sleeves 42 (Figs. I and V) slidably mounted on a non-circular portion of the shaft 41 and 70 provided with flanges 43 and 44. These sleeves 42 can be adjusted longitudinally of the shaft 41, as will be hereafter described. Each sleeve 42 is provided with a series of the gripping jaws 6 and 7, and I will now 75 describe the elements associated with one sleeve 42, it being understood that the other sleeve is provided with the same elements. 80 45 designates circular frame members (Figs. I and V) in the form of angle bars concentric with shaft 41 and rigidly secured to a flange 43 by means of bars 6' to which the gripping jaws 6 are rigidly secured. Each bar 6' may be riveted to a flange 43 on a sleeve 42, and also riveted to a circular 85 frame member 45. As shown by Fig. V, each gripping jaw 6 may be riveted to a pair of the bars 6'. Each gripping jaw 6 is 90 thus rigidly secured to its supporting frame. 95

Each gripping jaw 7 is formed on the outer end of an arm 7' having its inner end pivoted to a sleeve 42, as shown by Figs. I and V. 46 designates bell crank levers (Figs. I and V) pivoted to the rigid bars 6', each of said levers having a long arm 100 provided with a roller engaging one of the arms 7', and a short arm to which a tension spring 47 is secured. Each spring 47 operates with a bell crank lever 46 to force one of the gripping jaws 7 toward its companion gripping jaw 6. Immediately before a bag is forced into a gripping device, the jaw 7 is moved away from the jaw 6 to provide a space for the incoming bag, and as will be hereafter described, the jaw 7 is 105 afterwards released and restored by its spring 47 and bell crank lever 46, so as to grip the bag. The bag-turning rods 4 are then withdrawn from the bag while the latter is held by the grippers. After a number 110 of bags have accumulated in one of the gripping devices, all of the gripping devices can be moved about the axis of the shaft 41 to displace the collection of bags from the paths of the bag-turning rods, and to locate an empty gripping device at said paths. 115

Each gripping device includes two upper gripping jaws 6 (Fig. V) adapted to lie 120 above the corners of the bags A, and a pair 125

130

of gripping jaws 7 located below said jaws 6. The means for opening the gripping device includes a pair of rotary shafts 48 (Figs. I, V and VI) having their axes at 5 opposite sides of the gripping device. Each shaft 48 is provided with a pair of arms 49 and pressure fingers 50 extending from said arms. Each pressure finger 50 moves in a circular path about the axis of the shaft 48 10 to which it is secured, and the collection of bags in the gripping device lies in the paths of the pressure fingers. To open the gripping device, pressure fingers 50 press upon the top bag in the collection, with the result 15 of forcing the collection of bags downwardly, thereby moving the yieldable gripping jaws 7 downwardly relative to the rigid gripping jaws 6. During this operation, the pressure fingers 50 cooperate with 20 the yieldable gripping jaws to prevent displacement of the collection of bags. A bag can then be inserted into the gripping device, and after this has been done the pressure fingers 50 pass away from the bags to 25 release the yieldable gripping jaws 7, which are restored through the medium of springs 47. The shafts 48 are rotated in opposite directions, and the pressure fingers 50 move downwardly across the path of the bags 30 passing to the gripping device. As shown by Fig. V, the rigid gripping jaws 6 are provided with notches to receive the ends of the pressure fingers 50. Each finger 50 lies at an angle to the axis of its shaft 48, 35 and each gripping jaw 7 has an inclined outer edge conforming to that angle, as shown most clearly by Fig. V.

The means for rotating the shafts 48 includes bevel gears 51 shown by Figs. I and 40 V. Each bevel gear 51 meshes with a smaller bevel gear 52 fixed to the lower end of an inclined shaft 53 (Figs. I and III) the upper end of said shaft being provided with a gear 54 meshing with a gear 55 on one of 45 the rotary shafts 18. Owing to the speed reduction at the gears 51 and 52 (Fig. I), each shaft 48 turns only one-half of a revolution during each operation of the machine, but each shaft 48 is provided with two pressure fingers 50 so the gripping device is 50 opened in response to each operation of the machine.

The short shafts 18 transmit motion to various mechanisms that have already been 55 described, and each of these shafts is provided with a large driving gear 56 meshing with a pinion 57 on the main power shaft 59.

I will now point out the manner in which the machine can be adjusted to receive bags 60 of different widths. The means for supporting the various moving parts includes a stationary, or non-adjustable, main supporting frame, and a pair of adjustable supporting frames movably mounted on the main frame 65 and adjustable toward and away from each

other. The adjustable frames lie at opposite sides of the machine, and each of these frames carries approximately one-half of the mechanism. The main supporting frame comprises side frame members B rigidly connected together by means of an upper connecting member B' (Figs. I, III, IV and VII) and a lower connecting member B², the latter being shown in Fig. III. It is to be understood that these members B, B' and B² are rigidly secured together to form a stationary, or non-adjustable, main frame. There are two adjustable supporting frames, each comprising an upper frame member C (Figs. I, III, IV and VII), an arm C' extending rearwardly from said upper frame member, and a leg C² extending downwardly and forwardly from said upper frame member. As shown by Figs. I and VII, the arm C' is rigidly secured to the upper frame member C by means of bolts 60, and the leg C² is rigidly secured to said upper frame member by means of bolts 61. Each upper frame member C is slidably mounted on the stationary, or non-adjustable, frame member B' (Figs. I, III, IV and VII), the latter being horizontal and provided with longitudinal shoulders to receive guide bars 62 (Figs. I and VII) carried by and secured to the upper frame member C. It will now 95 be understood that each adjustable frame, including frame members C, C' and C², is slidably supported by the horizontal stationary frame member B', and that the adjustable frames can be moved toward and away from each other.

The means for moving the adjustable frames comprises a long, horizontal screw D (Figs. I, III and VII), rotatably mounted in bearings 63 on the stationary side frame members B, and having a right-hand thread 64 (Fig. III) and a left-hand thread 65. The arm C' forming part of one of the adjustable frames is provided with a nut 66 (Fig. III) to receive the right-hand thread, and the arm C' of the other adjustable frame carries a nut 66' to receive the left-hand thread. The screw D has a non-circular end 67 (Fig. III) to receive a tool whereby the screw can be turned in opposite directions 110 to move the adjustable frames toward and away from each other. The bag-holding elements and bag-turning elements are arranged in pairs on the adjustable supports so as to lie at opposite sides of the bags 115 where they cooperate with each other to support, turn and feed the bags. Each adjustable supporting frame comprising members C, C' and C², carries one of the oscillatory arms 8 provided with a pair of bag-holding members 2 and 3, as well as a bearing 37 for an arm 32 to which a bag-turning rod 4 is secured, and in addition to this each adjustable frame carries operating mechanism for the elements just referred to. Each 130

adjustable frame also carries one of the shafts 48 provided with a pair of fingers 50 to open a gripping device 6-7 at one side of the machine, and each of these frames 8 supports the mechanism for transmitting motion to its fingers 50.

More specifically stated, each adjustable frame is provided with a rotary shaft 18 (Figs. I and III) which, as heretofore pointed out, transmits motion to one of the bag-turning rods 4. Each shaft 18 is provided with a large gear 56 (Figs. I and VII) meshing with a pinion 57 on the main operating shaft 59. This main shaft is not adjustable, 15 but the pinion 57 is keyed to said shaft so the pinion can be adjusted longitudinally of the shaft to remain in mesh with the gear 56.

I will now point out the means for moving the gripping devices toward and away from each other in response to corresponding movements of the adjustable frames. As shown by Figs. I and V, each set of gripping devices is carried by a sleeve 42 slidably mounted on a non-circular portion of shaft 41, the latter being rotatably mounted in stationary bearings 68. Fig. V shows that each sleeve 42 is provided with an annular recess adapted to receive the rear end of one of the arms C'. When the adjustable frames 20 are moved toward or away from each other, the arms C' cooperate with sleeves 42 to impart a corresponding movement to the pairs of gripping elements. These elements serve as means for stripping the bags from the 25 bag-turning rods 4, and it will be apparent that they are adjusted with the other elements of the means for turning and feeding the bags.

I claim:

1. In a bag-turning machine, a bag-holder adapted to secure the mouth of the bag, a pair of bag-turning members having bag-engaging ends adapted to enter the mouth of the bag held by said holder, and means whereby said bag-engaging ends are advanced in curved lines diverging from said bag-holder, said means including pivots on which the respective bag-turning members are moved and the axes of said pivots being 50 at an angle to each other.

2. In a bag-turning machine, a bag-holder adapted to secure the mouth of the bag, a pair of bag-turning members having bag-engaging ends adapted to enter the mouth 55 of the bag held by said holder, and means whereby said bag-engaging ends are advanced in curved lines diverging from said bag-holder, said means including operating arms to which the bag-turning members are secured, pivotal supports for said operating arms, the axes of said pivotal supports being at an angle to each other, and operating means whereby said arms are oscillated about their respective axes to move the bag-engaging ends in said curved lines.

3. In a bag-turning machine, a bag-holder adapted to secure the mouth of the bag, a pair of bag-turning members having bag-engaging ends adapted to enter the mouth of the bag held by said holder, and means whereby said bag-engaging ends are advanced in curved lines diverging from said bag-holder, said means including pivoted operating arms to which said bag-turning members are secured, each bag-turning member being curved in a line approximately concentric with the axis of the pivoted arm to which it is secured, and the axes of said pivoted arms being at an angle to each other. 70

4. In a bag-turning machine, a bag-holder adapted to receive the mouth of the bag, a pair of bag-turning members having bag-engaging ends adapted to enter the mouth of the bag, and means whereby said ends are advanced in true arcuate lines diverging from the mouth of the bag, said means including pivotal supports with their axes at an angle to each other and driving mechanism whereby said bag-turning members 80 are oscillated about said axes. 85

5. In a bag-turning machine, a bag-holder, a pair of pivots arranged at an angle to each other, rigid arms extending from and secured to the respective pivots, curved bag-turning members secured to the respective arms and having bag-engaging ends adapted to enter the mouth of the bag held by said holder, and means whereby said arms and bag-turning members are moved 90 in arcuate paths about the axes of the respective pivots, so as to move said bag-engaging ends in arcuate lines diverging from the mouth of the bag. 95

6. In a bag-turning machine, a bag-holder adapted to secure the mouth of the bag, a pair of curved elastic bag-turning rods, a pair of pivoted arms secured to said curved elastic bag-turning rods, the axes of said pivoted arms being at an angle to each other, said curved elastic bag-turning rods having free ends adapted to enter the mouth of the bag, and means whereby said arms and rods are turned about said axes to advance said free ends in arcuate lines diverging from the mouth of the bag. 105

7. In a bag-turning machine, a bag-holder, a pair of elastic bag-turning rods adapted to enter a bag held by said bag-holder, a pair of pivotally supported operating arms to which said elastic rods are rigidly secured, said rods having free ends adapted to engage the corners at the closed end of the bag, the axes of said operating arms being at an angle to each other and each of said rods being curved in a line approximately concentric with the axis of its operating arm, and means whereby said arms and rods are oscillated about their respective axes to move said free ends of 110 115 120 125 130

the rods in lines diverging to the corners of the bag.

8. In a bag-turning machine, a bag-holder, a pair of pivotally supported arms, 5 curved bag-turning rods having bag-engaging ends adapted to enter the mouth of the bag, adjustable connections securing said rods to the respective arms, said adjustable connections including pivots on which said 10 rods are movable and securing means normally preventing such movement, and means whereby said rods and arms are oscillated about the axes of the arms.

9. In a bag-turning machine, a bag-holder 15 adapted to receive the mouth of the bag, a pair of bag-turning members having bag-engaging ends adapted to enter the mouth of the bag, pivoted arms secured to the respective bag-turning members, the axes of said 20 arms being at an angle to each other, and operating means whereby said arms are oscillated about their axes to advance said bag-engaging ends in lines diverging from the mouth of the bag.

25 10. In a bag-turning machine, a bag-holder adapted to receive the mouth of the bag, a pair of bag-turning members having bag-engaging ends adapted to enter the mouth of the bag, pivoted arms secured to the respective 30 bag-turning members, the axes of said arms being at an angle to each other, and operating means whereby said arms are oscillated about their axes to advance said bag-engaging ends in lines diverging from the mouth of the bag, said operating means including cranks yieldingly connected to said arms.

35 11. In a bag-turning machine, a bag-holder adapted to receive the mouth of the bag, a 40 pair of bag-turning members having bag-engaging ends adapted to enter the mouth of the bag, pivoted arms secured to the respective bag-turning members, the axes of said arms being at an angle to each other, and 45 operating means whereby said arms are oscillated about their axes to advance said bag-engaging ends in lines diverging from the mouth of the bag, said operating means including a pair of cranks movable about 50 parallel axes, and connecting rods through which motion is transmitted from said cranks to said arms.

55 12. In a bag-turning machine, a bag-holder adapted to receive the mouth of the bag, a pair of bag-turning members having bag-engaging ends adapted to enter the mouth of the bag, pivoted arms secured to the respective bag-turning members, the axes of said arms being at an angle to each other, and 60 operating means whereby said arms are oscillated about their axes to advance said bag-engaging ends in lines diverging from the mouth of the bag, said operating means including a pair of cranks movable about

parallel axes, and connecting rods through which motion is transmitted from said cranks to said arms, said connecting rods being provided with ball and socket connections permitting movement of said arms about the first mentioned axes. 65 70

75 13. In a bag-turning machine, a bag-holder including a pair of bag-holding members adapted to extend into the bag, a pivotal support for one of said bag-holding members, a spring whereby the pivotally supported bag-holding member is forced away from the other bag-holding member to frictionally secure the bag, a bag-turning member whereby the bag is stripped from said bag-holding members, and means whereby the pivotally supported bag-holding member is forced toward the other bag-holding member to receive the mouth of the bag, said means including a driving member and a driven member normally separated from said driving member to permit operation of said spring. 80 85

90 14. In a bag-turning machine, a bag-holder including a pair of bag-holding members adapted to extend into the bag, a pivotal support for one of said bag-holding members, a spring whereby the pivotally supported bag-holding member is forced away from the other bag-holding member to frictionally secure the bag, a bag-turning member whereby the bag is stripped from said bag-holding members, and means whereby the pivotally supported bag-holding member is forced toward the other bag-holding member to receive the mouth of the bag, said means including a cam and a driven member actuated thereby, said driven member being normally separated from said cam to permit the functioning of said spring. 95 100

105 15. In a bag-turning machine, a bag-holder including bag-holding members adapted to extend into the bag, a movable bag-turning member cooperable with said bag-holding members to turn the bag, a carrier to which said bag-holding members are secured, a pivotal support for said carrier, means for moving said carrier about the axis of said pivotal support to move said bag-holding members away from the path of said bag-turning member, and means whereby one of said bag-holding members is moved toward and away from the other. 110 115

120 16. In a bag-turning machine, a bag-holder including bag-holding members adapted to extend into the bag, a movable bag-turning member cooperable with said bag-holding members to turn the bag, a carrier to which said bag-holding members are secured, a pivotal support for said carrier, means for moving said carrier about the axis of said pivotal support to move said bag-holding members away from the path of said bag-turning member, and means

whereby one of said bag-holding members is moved toward and away from the other, the last mentioned means including a pivotal connection near the axis of said 5 pivotal support.

17. In a bag-turning machine, a bag-holder including bag-holding members adapted to extend into the bag, a movable bag-turning member cooperable with said 10 bag-holding members to turn the bag, a carrier to which said bag-holding members are secured, a pivotal support for said carrier, means for moving said carrier about the axis of said pivotal support to move said 15 bag-holding members away from the path of said bag-turning member, one of said bag-holding members being pivoted to said carrier, and means whereby the pivoted bag-holding member is moved toward and 20 away from the other bag-holding member, the last mentioned means including a pivot near the axis of said pivotal support.

18. In a bag-turning machine, a pair of oscillating carriers each provided with a 25 pair of bag-holding arms, a movable bag-turning member cooperable with said arms to turn the bag, one of the arms of each pair being rigidly secured to one of the oscillatory carriers and the other being 30 pivoted to the carrier, means whereby said carriers are oscillated to and from bag-receiving positions beyond the path of said bag-turning member, and means whereby the pivoted arms are moved toward and 35 away from the rigidly secured arms.

19. In a bag-turning machine, a bag-holder including bag-holding members, a movable bag-turning member cooperable with said bag-holding members to turn the 40 bag, and means whereby said bag-holder is shifted to a bag-receiving position beyond the path of said bag-turning member, said means including a crank connected to said bag-holder and a rack and pinion whereby 45 said crank is actuated.

20. In a bag-turning machine, a bag-holder including bag-holding members adapted to extend into the bag, a movable bag-turning member cooperable with said 50 bag-holding members to turn the bag, a carrier to which said bag-holding members are secured, a pivotal support for said carrier, means for moving said carrier about the axis of said pivotal support to move said 55 bag-holding members away from the path of said bag-turning member, said means including an oscillatory crank, a connecting rod connecting said crank to said carrier, a pinion secured to said crank, a rack meshing 60 with said pinion, and a driving crank pivoted to said rack.

21. In a bag-turning machine, a pair of supports each provided with a bag-turning member and a holding member for the bag

to be turned, one of said supports being adjustable toward and away from the other to provide a corresponding adjustment of its bag-turning and holding members.

22. In a bag-turning machine, a pair of supports each provided with a bag-turning member, a holding member for the bag to be turned and operating means for said members, the members and operating means being arranged in pairs on the different supports so as to cooperate with each other in turning a bag, and means whereby one of said supports is adjusted toward and away from the other to provide a corresponding adjustment of its bag-turning and holding members and their operating means.

23. In a bag-turning machine, a pair of supports each provided with a bag-turning member, a holding member for the bag to be turned and operating means for said members, the members and operating means being arranged in pairs on the different supports so as to cooperate with each other in turning a bag, and a right and left adjusting screw whereby said supports are 100 moved toward and away from each other to provide a corresponding adjustment of the companion members of each of said pairs.

24. In a bag-turning machine, a pair of supports each provided with a bag-holding device adapted to hold one side of the bag, a bag-turning device movable in one side of the bag and operating means for said devices, the devices and operating means being 105 arranged in pairs on the different supports, and one of said supports being adjustable toward and away from the other to vary the distance between the companion elements of said pairs.

25. In a bag-turning machine, a pair of supports each provided with a bag-holding device adapted to engage one side of the bag, a bag-turning device movable in one side of the bag, a stripping device adapted 110 to receive the bag from said turning device, and operating means for all of said devices, the operating means and devices being arranged in pairs on the different supports so as to cooperate with each other at opposite sides of the bag, and means whereby one of said supports is adjusted toward and away from the other to vary the distance between the companion members of each of 115 said pairs.

26. In a bag-turning machine, a pair of supports each provided with a bag-holding device adapted to frictionally engage one side of the bag, a pivoted bag-turning device movable in one side of the bag, a gripping device adapted to receive a portion of the bag from said turning device, an opening device for said gripping device and 120

operating means for all of said devices, the operating means and devices being arranged in pairs on the different supports so as to cooperate with each other at opposite sides of the bag, and means whereby one of said supports is adjusted toward and away from the other to vary the distance between the companion members of each of said pairs.

27. In a bag-turning machine, a pair of supports each provided with a bag-holding device adapted to frictionally engage one side of the bag, a pivoted bag-turning device movable in one side of the bag, a gripping device adapted to receive a portion of the bag from said turning device, an opening device for said gripping device and operating means for all of said devices, the operating means and devices being arranged in pairs on the different supports so as to cooperate with each other at opposite sides of the bag, and a right and left adjusting screw whereby said supports are moved to-

ward and away from each other to vary the distance between the companion members of each of said pairs.

25

28. A bag-turning machine provided with a pair of pivotally supported curved bag-turning arms movable in diverging arcuate paths conforming approximately to their curvatures, and a bag-holder whereby the bag is held in said diverging arcuate paths.

29. A bag-turning machine provided with a pair of pivotally supported curved bag-turning arms movable in diverging arcuate paths conforming approximately to their curvatures, and a bag-holder whereby the bag is held in said diverging arcuate paths, the pivotal supports being so arranged that the pivotal motion alone will cause the bag-turning arms to travel in said diverging arcuate paths.

35

In testimony that I claim the foregoing I hereunto affix my signature.

BIRNEY C. BATCHELLER.
